UNITED STATES PATENT OFFICE.

JOHN HOLM, OF BUTTE, MONTANA.

TRUNK.

Application filed November 2, 1925. Serial No. 66,332.

My invention relates to improvements in trunks, more especially in those forms of trunks designated as wardrobe trunks, and it consists in the combinations, constructions, and arrangements herein described and claimed.

An object of my invention is to provide a trunk which has the appearance of the ordinary wardrobe trunk, but which may be extended for use as a wardrobe, thereby accommodating clothes of greater length than that of the ordinary trunk, such as trousers, top coats, and the like.

A further object of my invention is to provide a device of the type described having means for readily permitting the extension of the trunk or the collapsing of the same so as to provide a trunk of the ordinary size.

20 A further object of my invention is to provide means for closing the trunk in its extended condition, thereby keeping dust from the interior when it is used as a wardrobe.

25 A further object of my invention is to provide a plurality of drawers or chests with a single locking means, whereby all of the drawers or chests may be locked at one operation.

30 A further object of my invention is to provide a novel form of handle for the drawers as well as the trunk itself which can be cheaply made, and which takes up relatively little room.

35 Other objects and advantages will appear in the following specification, and the novel features of the invention will be particularly pointed out in the appended claims.

My invention is illustrated in the accompanying drawings, forming part of this application, in which—

Figure 1 is a perspective view of the device in its collapsed position,

45 Figure 2 is a face view showing the arrangement of the drawers and the means for covering the goods contained in the trunk,

Figure 3 is an enlarged sectional view of the trunk in its extended position,

50 Figure 4 is a perspective detail view of a locking bar,

Figure 5 is a section along the line 5—5 of Figure 2,

55 Figure 6 is a section along the line 6—6 of Figure 2,

Figure 7 is a detail sectional view along the line 7—7 of Figure 2, and

Figure 8 is a detail perspective view of a removable brace member.

In carrying out my invention I make use 60 of a body portion 1 and a top or cover portion 2, these being hinged together at 3 in the ordinary manner. The trunk is provided with the ordinary corner braces 4 and the reinforcing strips 5 similar to any wardrobe trunk. The outside of the body portion as well as the top may have any suitable covering, such as that shown at 6.

Hinged to one end of the body portion 1 is a dust protector which is itself made up 70 of hinged sections, such as those shown at 7, 8 and 9 in Figures 2 and 6. It will be noted that the section 7 is smaller in width than the other sections. This is for the purpose of folding this dust protector back 75 upon the end of the trunk in the manner shown in dotted lines in Figure 6.

Normally disposed within the body portion is an extension having sides 10 and 11, 80 see Figure 3, and an end 12 which constitutes in fact the end of the trunk when it is in its closed position. The extension has a rear portion 13. The rear portion and the sides are arranged to slide within the main body portion 1, the back 13 of the extension bearing on the back 14 of the body portion, see Figure 3, and the front edges of the sides 10 and 11 being guided by flanges 15 and 16. On each of the sides 10 and 11 is a

85 spring member 17 which is fastened at the upper end as shown at 18 in Figure 3, and which is provided at its lower end with a latching member 19 arranged to enter a lower opening 20 in the body portion when the trunk is collapsed, or an upper opening 21 90 when the trunk is in its extended position.

In the drawings, I have shown these latching members 19 as being of cylindrical form. Each of the latching members has attached thereto a pull strap 22 by means of which 100 the latching member 19 may be swung clear of the opening, thus permitting the sliding of the extension.

In Figure 8, I have shown in detail a brace bar. This brace bar is arranged to extend across from side to side of the trunk and to engage in slots provided in ears 23 carried by the flanges 15. The brace bar is really made in two parts. One of these parts 24, see Figure 8, has an offset 29 to 105 110

form a groove 30. The other part 31 has a tongue 32 at its end arranged to enter the groove while a slidable sleeve 33 is provided which is arranged to hold the overlapped portions 24 and 31. The sleeve is provided with a latch member 34 consisting of a flat button having a shank pivotally mounted on the sleeve.

As will be observed from Figure 2, there is a plate 35 on the central section of the dust protector 8 which has a slot arranged to receive the latch member 34, which when turned at right angles to the slot will hold the dust protector in position.

The cover portion 2 of the trunk contains drawers 36 at one end (the top in Figure 2), while three drawers 37, 38 and 39, respectively, are disposed below the drawers 36. In order to provide for simultaneous locking and release of these drawers, I make use of a lock bar 40, such as shown in detail in Figure 4. This locking bar, it will be observed, has at one end a curved tongue 42 which is arranged to enter an opening in an ear 43 secured to a partition 44. The opposite end of the bar is provided with a keeper 45 arranged to enter an opening 46 in the upper partition 47 so as to prevent longitudinal movement. The bar 40 is provided with a keyhole 48 which registers with a lock 49 on the drawer 37. At 50, I have shown a handle which is made by punching out a portion of the bar 40.

Each of the drawers is provided with an individual handle 51. This handle is formed by a single sheet of metal stamped so as to provide triangular shaped end portions 52 with a central cylindrical portion joining said end portions. The handles are disposed across recesses 53 in the front walls of the drawers. When it is desired to lock the drawers, the tongue 42 of the locking bar is slipped through the opening in the ear 43, and the bar is brought into position with the keyhole 48, registering with that in the lock 49. The keeper 45 is provided with an opening 45^a so that when the lock is turned, the bolt will pass through the opening 45^a, thus holding the keeper securely to the partition 47, see Figure 5. The bar 40, it will be noted, overlies all of the drawers so that none of the drawers can be removed until the locking bar is released. A turn of the key will release the locking bar, which can then be removed by the handle 50, thus giving access to all the drawers immediately.

In the upper part of the body portion 1 is a slidable frame 54, which runs on guides 55, see Figure 3, and upon which may be supported clothes hangers 56 of any suitable form. The construction is such that the frame 54 may be pulled out to obtain access to the clothes hangers and may be pushed in when desired.

From the foregoing description of the various parts of the device, the operation thereof may be readily understood. In packing the trunk, the brace bar portions 24 and 31 are disconnected, or even removed, so as to give free access to the interior of the body portion. In order that free access may be had, the dust protector is thrown back over the top, as indicated in Figure 6 in dotted lines. When the body portion of the trunk has been packed, then the brace members 24 and 31 are swung together, and the slidable sleeve 33 is moved to the position shown in Figure 8 to lock the portions together. The dust protector may now be swung downwardly, the latch 34 being turned to pass through the slot in the plate 35, and then turned at right angles to latch it in the position shown in Figure 2. Normally, there is a separate removable section 57 to the dust cover which is designed to be used when the trunk is extended. A portion of this cover section is shown in Figure 3. It will be observed that it has a plate 58 having an opening arranged to receive the latch member 34, and normally this extra section is carried just beneath the lowest section 9 of the dust cover.

When it is desired to extend the trunk so as to use it as a wardrobe, the hinged dust cover portions are first unlatched and then thrown back into the position shown in Figure 6. The latch member 34 is then turned so as to permit the removal of the dust cover portion 57, thus giving access to the interior of the trunk. The straps 22, which are secured to the spring latch members 19, are pulled inwardly and upwardly, and this first causes the latch members 19 to withdraw from the lower openings 20, and the extension to be lifted until the latch members 19 reach the upper openings 21, see Figure 3, when they will enter these openings and thus maintain the trunk in its extended position. Garments may now be hung on the hangers and the full height of the extending trunk utilized as a wardrobe. In order to cover the entire trunk as extended, it is only necessary to replace the dust cover portion 57, latching it to the catch 34, and then to bring down the hinged portions of the dust cover section which will register with the upper edge of the removable portion 57, and thus the trunk, as extended, will be covered. It will be observed from Figure 3 that the plate 58 extends slightly above the upper edge of the auxiliary dust cover portion 57, so as to hold the lower portion of the dust cover section 9 securely in position.

It will be noted that the reinforcing strips 5, see Figure 1, on the slidable portion of the trunk, as well as the corner braces 4, overlap the lower body portion 1 when the trunk is closed so that the appearance of

the two ends of the trunk are the same, and there is no indication on the outside of the trunk that it is an extension trunk, or that it is any different from the ordinary ward-
robe trunk.

It will also be noted that the brace member serves not only to keep the clothes in place and to brace the trunk, but it serves as a medium for latching the dust protector
10 portions in position.

I claim:

1. A trunk comprising a body portion, a
slidable telescopic extension disposed nor-
mally within said body portion, one end
15 of said extension comprising a closure for
the body portion, a foldable dust protector
hinged to said end, means for retaining the
extension normally within said body por-
tion and for retaining it in its extended
20 position, and an auxiliary dust protector
section arranged to cooperate with said first

named dust protector for covering the ex-
tension and the body portion when the ex-
tension is in its extended position.

2. A trunk comprising a body portion, a 25
slidable telescopic extension disposed nor-
mally within said body portion, one end of
said extension comprising a closure for the
body portion, a foldable dust protector
hinged to said end, means for retaining the 30
extension normally within said body portion
and for retaining it in its extended posi-
tion, an auxiliary dust protector section ar-
ranged to cooperate with said first named
dust protector for covering the extension 35
and the body portion when the extension is
in its extended position, a removable brace
member carried by said body portion, and
means carried by said brace member for
latching the dust protector in position.

JOHN HOLM.
